UNITED STATES PATENT OFFICE.

RUSSELL A. HART, OF BATTLE CREEK, MICHIGAN.

WAGON-BOX.

SPECIFICATION forming part of Letters Patent No. 412,746, dated October 15, 1889.

Application filed August 26, 1889. Serial No. 322,004. (No model.)

To all whom it may concern:

Be it known that I, RUSSELL A. HART, a citizen of the United States, residing at Battle Creek, county of Calhoun, State of Michigan, have invented a new and useful Wagon-Box, of which the following is a specification.

This invention relates to wagon-boxes which have sectional sides, so as to convert the box from one condition to another for various uses; and it has for its object the peculiar construction of stakes in sections attached to the ordinary wagon-box, said sections being detachable from each other and provided with side-boards, substantially as below described and claimed.

In the drawings forming a part of this specification, Figure 1 is a transverse section of a wagon-box, showing the stakes in elevation. Figs. 2, 3, and 4 are lettered details from Fig. 1, illustrating some of the adjustments; Fig. 5, an enlarged section on line 2 in Fig. 1, looking from a point above said line; Fig. 6, lettered broken details showing a change below described, and Fig. 7 is a section on line 33 in Fig. 6, looking from a point above.

Referring to the lettered parts of the drawings, A is a wagon-box. The base or lower sections of the stakes are shown at B. These sections are attached to the wagon-box at the sides outside of the side-boards E, near the front and rear ends of said box, and at or near the center, as Fig. 1 will serve to illustrate, as regards the stakes at one end, the other stakes (not shown) being the same in construction. More than three of the stakes may be employed at each side of the box, if found necessary. It should be borne in mind that these sectional stakes do not take the place of the stakes of the bolsters in the ordinary wagon, but are independent of said bolster-stakes, and are, as stated, attached to the box itself.

The sections B in Figs. 1, 2, 3, and 4 are provided on one side near the upper end with projections *i* and a screw-threaded pivot *a*, Fig. 5. The lower end of the section C in said figures is provided with a fulcrum-hole, into which the fulcrum-pivot *a* is passed, and with rows of holes in lines radiating from said fulcrum to receive the projections *i* to hold the

section C at different angles. The upper end of section C has a series of holes in like relation with each other, and with the fulcrum-pivot *t* (like *a* on top of section B) and the projection *e*, (like *i* on top of section B.)

The number of the projections and holes is a matter of choice, according to the strength required, only one projection being here shown on lower end of the section D and two on top 60 of the section B. This latter section is stationary, while the sections C D are adjustable and detachable.

Figs. 6 and 7 show the pivot *a* and projections on the lower end of the section C, instead 65 of on the upper end of the fixed section B. This construction is preferable, inasmuch as the projections are all removed when the upper sections C D are both detached, thus leaving no projections on the section B to catch 70 against anything. It will be observed that the pivots *a* *t* are longer than the projections *i* *e*, and are provided with nuts to bind the sections firmly together.

The object of having the pivots longer than 75 the projections is in order that the nuts can be screwed off far enough (but not entirely off) to allow the sections to be slipped off from the projections to tilt them to different angles and allow the projections to pass into 80 another series or row of holes without entirely detaching said sections.

The sections of the stakes have side-boards attached to them on the inside, so that when the sections are at a vertical angle, as in Fig. 85 1, they make a much deeper box than when only a part of the sections are used. When, as in Fig. 2, the section C is tilted outwardly and the upper section to the dotted horizontal position, a convenient hay-rack is formed. 90 In Fig. 1 the dotted positions show other angles.

In Fig. 4 the upper section has been detached and the section C is at a horizontal angle. When the sections are in this position, they may serve as side seats to the wagon-box, but without a back to the seats. The dotted position of section C in this figure shows a rack of less dimensions than that shown in Fig. 2.

In Fig. 3 the sections C D are so arranged as to form a seat with a back, so that the

wagon can serve as a carry-all. In this use of the upper sections they are reversed—that is, the sections D D in Fig. 1 are changed places with, so that the seat of the horizontal part 5 C will have a back, and at the same time the side-boards of each section C D will not conflict with each other.

Having thus described my invention, what I claim as new is—

10 A wagon-box having sectional sides, said sides consisting of the base fixed sections comprising sections of stakes having side-boards attached thereto and additional like sections,

all of which sections are detachably and adjustably attached to each other by means of 15 the fulcrum-pivots, the projections, the fulcrum-holes, and the holes to receive the projections, substantially as set forth.

In testimony of the foregoing I have hereunto subscribed my name in presence of two 20 witnesses.

RUSSELL A. HART.
